UNITED STATES PATENT OFFICE.

ORTON C. LITTLE, OF MENASHA, WISCONSIN.

SLIDING SHOE FOR FURNITURE.

No. 822,963.

Specification of Letters Patent.

Patented June 12, 1906.

Application filed June 9, 1905. Serial No. 264,700.

To all whom it may concern:

Be it known that I, ORTON C. LITTLE, a citizen of the United States, residing at Menasha, in the county of Winnebago and State of Wisconsin, have invented a new and useful Improvement in Sliding Shoes for Furniture, of which the following is a specification.

My invention relates to a device for use upon furniture-legs or upon other articles which it is desired to move a short distance instead of the common wheel-casters, and it is designed also for application to the rear legs of chairs, particularly office-chairs in hotels, club-rooms, professional men's offices, &c., for the purpose of allowing the tipping backward of the chairs without the floor or the floor-covering being in any way injured or defaced by the legs of the chairs, and it also relates to the application of a pad of fabric to the shoe for use upon hard-wood or other glassy floors, it comprising a circular shoe to be applied to the furniture for supporting it upon the floor, it having a flat bottom with upwardly-curved outer edge, and those intended for chairs sometimes being provided with a cavity on its under side into which a pad of fabric is to be secured by means of cement or otherwise, said pad projecting below the outer edge of the shoe. Rising centrally from the upper side of the shoe a curved top support for a socket is arranged, the socket being arranged to oscillate upon said support and being adapted to be detachably connected by means of a round pin to the article to be supported by the shoe, said pin being for most purposes preferably of the kind known as a "split" pin.

Among the advantages of this shoe over the usual wheel-caster, are the large surface which it presents for the support of the article to be moved in comparison with the surface of a wheel of narrow face and small diameter, and it being of circular form it can slide in any direction, which a small caster-wheel will not do, and, furthermore, when sliding it will not be liable to mar the floor or tear the carpet, which faults are of common occurrence in the use of the usual casters. By means of the support with its curved top a universal joint is provided, which, although confined in its movement within prescribed limits, is ample for all occasions likely to occur,—such as lubricating the joint, tilting a chair backward, or moving the various articles for which the shoe is adapted.

My invention is illustrated in the accompanying drawings, in which—

Figure 1 is a vertical section of one form of the shoe as applied to chairs and also showing a pad of fabric attached to the shoe. Fig. 2 is a plan showing the upper side of the shoe. Fig. 3 is a plan showing the under side of the socket which is carried upon the curved top or the centrally-arranged support of the shoe. Fig. 4 is a vertical section showing a modified construction of a shoe intended to be cast from a suitable metal and designed for heavier furniture than the one shown in Fig. 1. Fig. 5 is a plan showing the upper side of the shoe that is shown in Fig. 4. Fig. 6 is a vertical section showing a shoe intended to be formed of a suitable earthenware material and may be used on pianos, book-cases, and other heavy articles. Fig. 7 is a vertical section of a piece of furniture and showing a split pin, in elevation, inserted in said furniture, the pin having the socket which is shown in Figs. 4 and 6 upon its lower or closed end. Fig. 8 shows a form of shoe similar to that shown in Fig. 1, but having a different method by which it is connected with the pin. Fig. 9 is a plan of the support for the socket which is shown in Fig. 6. Fig. 10 is a side elevation of a split pin. Fig. 11 is a plan of the housing used in Fig. 6. Fig. 12 is a plan of the housing shown in Fig. 8. Fig. 13 is a plan of the lower side of the shoe, as shown in Fig. 1.

Similar numerals indicate like parts in the several views.

In Fig. 1, 1 indicates the sliding shoe formed by stamping it from a suitable sheet metal, the concentrically-arranged support 2 having the central perforation 3, said perforation being of sufficient diameter for allowing the shoe to oscillate upon the pin 4 the necessary amount, a washer 5 being placed between the socket-piece 6 and head 7 of the pin, so that the shoe can oscillate easily. The pin can be a solid round pin, as in Fig. 1, or a split pin, as in Figs. 4, 6, 7, 8, and 10.

Split pins are not a new device, but as far as I am aware they have never been applied in the manner herein shown, but have been inserted entirely through a bore in a part upon which it was desired to retain another part instead of detachably connecting two parts, as herein shown. This pin is formed by bending a bar of half-round spring metal until the flat sides of its two ends nearly meet

each other and by forming a small head or enlargement upon its closed end. The purpose of said head is to hold the pin from passing entirely through an aperture into which the pin is inserted, and in some cases it may be more convenient to form a thread upon said closed end and secure thereto a part larger than the pin and forming thereby a detachable head.

10 In the modification Fig. 4 the shoe 1^a is formed by casting it from a suitable metal, the support 2^a having its apex removed and its upper end so shaped as to provide space for the head 7 of the split pin 4^a. The socket 6^a is formed by stamping it from sheet metal, as is also the housing 12, which housing has its outer edge turned over the outer edge of the shoe and its central perforation 13 formed of a sufficient diameter for the oscillation of 15 the shoe under the socket, said central perforation having a lip 14 turned downward for engaging the outer curve of the socket 6^a.

The modification shown in Fig. 6 has its shoe 1^b formed of earthenware material, 20 which material when properly glazed will present a very hard and glassy surface for sliding over a floor or carpet. A socket 15 is formed, into which a supporting-piece 16, stamped from sheet metal, is inserted, the 25 supporting-piece having the curved upper surface socket-support 2^b, having the perforation 3^b for giving space for the head of the attaching-pin. The outer edge of the piece 16 is bent over and is carried upon the ledge 30 18, which is formed in the shoe. The elevated part 19 of the shoe is provided with an undercut 20 around its outer edge, into which the outer edge 17 of the housing 12^b is turned, the housing, like the one described 35 35 from the floor.

Fig. 8 shows a form of shoe 1^c substantially the same as is shown in Figs. 1 and 4, formed, as in Fig. 1, by stamping it from sheet metal instead of casting it, as in Fig. 4. The 40 socket 6^a is applied to the shoe the same as in Fig. 4; but the housing 12^c is fitted around the socket-piece by turning a lip 14 upward around its central opening for engaging the curved outer surface of the socket-piece.

5 The only need of the housing is to lift the shoe whenever it is necessary to raise the article to which the shoe may be attached and to hold the shoe so near the socket upon the pin that when the article moved is again 10 placed upon the floor the shoe and socket will assume their normal position relative to each other.

In Figs. 1 and 13, 10 indicates a cavity into which a fabric pad 11 is inserted for a purpose heretofore described.

Having described my invention, what I claim, and desire to secure by Letters Patent, is—

1. A sliding shoe for furniture, or other articles, having a flat lower surface and upwardly-curved outer edge, a support arranged concentrically within the shoe having a portion of its upper surface between its vertical sides and top and provided with an outwardly-curved surface, a socket fitted to oscillate upon said curved surface within prescribed limits, and a pin arranged to pass through said socket and being adapted to be engaged by a bore in a suitable piece having a diameter corresponding with the diameter 75 of said pin, and a depth equal to the length of the pin required to be used in said bore, and means for preventing the separation of said concentrically-arranged support and socket, substantially as described. 85

2. A sliding shoe for furniture, or other articles, having a flat lower surface and upwardly-curved outer edge, a support arranged concentrically within the shoe having a portion of its upper surface between its vertical sides and top provided with an outwardly-curved surface, a socket fitted to oscillate upon said curved surface within prescribed limits, and a split pin arranged to 90 pass through said socket and being adapted to be engaged by a bore in a suitable piece having a diameter corresponding with the diameter of said pin when compressed to its smallest dimensions, and a depth equal to the length of the pin required to be used in said bore, and a housing connecting said concentrically-arranged support and socket and preventing their separation, substantially as described. 95 100

3. A sliding shoe for furniture, or other articles, formed of earthenware material, having a flat lower surface and upwardly-curved outer edge, means for securing a housing concentrically around and over a portion of its upper surface, a socket formed centrally 110 within the upper surface of the shoe, a supporting-piece mounted concentrically within said socket having a central aperture and a portion of its upper surface between its vertical sides and said aperture curved outwardly, in combination with a pin having a head or enlargement upon its closed end and a socket secured to said pin and being adapted to oscillate within prescribed limits upon the aforesaid supporting-piece, and means 115 for preventing the separation of said last-named socket and the shoe by the application of a housing substantially as shown. 12

4. A sliding shoe for furniture, or other articles, formed of earthenware material, having a flat lower surface and upwardly-curved outer edge, means for securing a housing concentrically around and over a portion of its upper surface, a socket formed centrally 120 within the upper surface of the shoe, a sup- 13

porting-piece mounted concentrically within said socket having a central aperture and a portion of its upper surface between its vertical sides and said aperture curved outwardly, in combination with a split pin having a head or enlargement upon its closed end and a socket secured to said pin, it being adapted to oscillate within prescribed limits upon the aforesaid supporting-piece, said pin being adapted to enter a bore in a suitable piece having a diameter corresponding with

the diameter of said pin when compressed to its smallest dimension, and a depth equal to the length of pin required to be used in said bore, and means of preventing the separation of said last-named socket and the shoe by the application of a housing, substantially as shown.
